UNITED STATES PATENT OFFICE.

JOHN F. O'CONNOR, OF CHICAGO, ILLINOIS, ASSIGNOR, BY MESNE ASSIGNMENTS, TO
WILLIAM H. MINER, OF CHICAGO, ILLINOIS.

ANTIFRICTION CENTER-BEARING FOR RAILWAY-CARS.

953,054.

Specification of Letters Patent. Patented Mar. 29, 1910.

Application filed May 4, 1907. Serial No. 371,785.

To all whom it may concern:

Be it known that I, JOHN F. O'CONNOR, a citizen of the United States, residing in Chicago, in the county of Cook and State of Illinois, have invented a new and useful Improvement in Antifriction Center-Bearings for Railway-Cars, of which the following is a specification.

My invention relates to anti-friction center bearings for railway cars. Its object is to provide an anti-friction center bearing for railway cars or other vehicles of a simple, strong, efficient and durable construction in which the anti-friction conical rollers between the upper and lower center plates may be kept in their proper radial relation for efficient operation, and in which at the same time as large a number of rollers as possible may be employed in order that the heavy load upon the center plate may be distributed among as large a number of rollers as possible.

My invention consists in the means I employ and herein shown and described for practically accomplishing this result. That is to say, it consists in connection with the upper and lower center plates having annular conical treads and an annular train of closely adjacent conical rollers between the upper and lower bearing plates and a roller alining arm or arms extending radially between adjacent rollers of the train at one or more points to keep the rollers from skewing, and to cause them to preserve their radial arrangement, and means for keeping said radial roller alining arm or arms in its proper radial position as it travels with the rollers around the annular tread of the center plates.

My invention also consists in the novel construction of parts and devices, and in the novel combinations of parts and devices herein shown and described.

In the accompanying drawing forming a part of this specification, Figure 1 is a central vertical section of an anti-friction center bearing embodying my invention. Fig. 2 is a plan view partly in horizontal section. Fig. 3 is a detail end view of the roller alining radial arm with its integral ring for keeping it in radial position as it travels around the annular tread of the center plates.

In the drawing, A represents the body

bolster of a railway car or other vehicle, and B the upper center plate secured thereto.

C is the truck bolster, D the lower center plate secured thereto and E is a king bolt.

F F F are a series or train of closely adjacent conical rollers arranged radially between the annular conical tread b of the upper center plate B and the annular conical tread d of the lower center plate D. The upper center plate B has an annular hub b¹ surrounding the king bolt E and an annular rim b² and the lower center plate D has an annular hub d¹ which surrounds the annular hub b¹ of the upper center plate B and the lower center plate D has an annular rim d² which fits within the annular rim b² of the upper center plate B. The annular hubs and rims of the center plate thus telescope with each other.

G is my traveling roller alining radial arm interposed at one or more points in the circumference of the annular train of rollers F, the same being provided with an annular ring G¹ surrounding the annular hub d¹ of the lower center plate D to keep the radial arm in its radial position as it travels around with the train of rollers. This radial roller alining arm G is preferably furnished with curved sides g conforming to the periphery of adjacent rollers F F between which it is interposed and it is also made tapering and wider at its outer end than at its inner end. If preferred, two roller alining radial arms G G may be employed at diametrically opposite points of the train of rollers F F, but ordinarily I find one radial arm sufficient to keep the train of adjacent rollers F F each in proper radial position and to prevent their becoming askew as they travel around the annular tread. In case two diametrically opposite roller alining arms G G are employed as indicated in the drawing, they are both preferably made integral with the ring G¹ by which they are held in radial relation.

Whether one or two roller alining arms G are employed, each and every one of the rollers of the complete circular train contacts directly with at least one adjacent roller. And all of the rollers excepting those which contact with the arm or arms G of course directly contact with two adjacent rollers, whether one or two alining arms G are employed. By train of rollers, I wish

to be understood as meaning a complete circle of rollers extending around the annular treads of the bearing plates.

As the rollers F F are in close juxtaposition to each other, a very large number of rollers may be interposed between the center plates and the load and wear thus distributed among a very large number of rollers.

As the rollers F are each a plain frustum of a cone, they may be very readily and cheaply formed and as they have no sets or reduced ends liable to be broken off, they are also durable and little liable to fracture or injury.

15 The hub of the upper bearing plate B has a thinned and preferably notched rim b³ having notches b⁴ at its lower end, adapted to be clenched or upset against the shoulder d³ of the hub of the lower bearing plate D to lock the two bearing plates together with the interposed rollers and the roller alining arm G. The upper bearing plate B is preferably provided with an upper shell B¹ in a separate piece from the conical tread carrying portion of said upper bearing plate.

I claim:

1. In an anti-friction center bearing for railway cars, the combination with upper and lower center plates having annular conical treads and interfitting annular hubs, of a circular train of radially arranged conical rollers between said upper and lower plates, and a roller alining radial arm interposed between two adjacent rollers of said circular train to keep the rollers from becoming askew and to maintain them each in proper radial arrangement, said rollers filling and covering said annular tread and all said rollers, excepting those having radial arm engagement, directly contacting each with two adjacent rollers of the circular train, substantially as specified.

2. In an anti-friction center bearing for railway cars, the combination with upper and lower center plates having annular conical treads and interfitting annular hubs, of a circular train of radially arranged conical rollers between said upper and lower plates, and a roller alining radial arm interposed between two adjacent rollers of said circular train to keep the rollers from becoming askew and to maintain them each in proper radial arrangement, said rollers filling and covering said annular tread, and all said rollers, excepting those having radial arm engagement, directly contacting each with

two adjacent rollers of the circular train, said roller alining radial arm having an integral ring fitting the annular hub of one of said center plates to keep it in its proper radial position as it travels around with the rollers, substantially as specified.

3. In an anti-friction center bearing for railway cars, the combination with upper and lower center plates having annular conical treads and interfitting annular hubs, of a circular train of radially arranged conical rollers between said upper and lower plates, and a roller alining radial arm interposed between two adjacent rollers of said circular train to keep the rollers from becoming askew and to maintain them each in proper radial arrangement, said rollers filling and covering said annular tread, and all said rollers, excepting those having radial arm engagement, directly contacting each with two adjacent rollers of the circular train to keep the rollers from becoming askew and to maintain them each in proper radial arrangement, said rollers filling and covering said annular tread, and all said rollers, excepting those having radial arm engagement, directly contacting each with two adjacent rollers of the circular train, said roller alining radial arm having an integral ring fitting the annular hub of one of said center plates to keep it in its proper radial position as it travels around with the rollers, said center plates having also interfitting annular rims, substantially as specified.

4. In an anti-friction center bearing for railway cars, the combination with upper and lower center plates having annular conical treads and interfitting annular hubs, of a circular train of radially arranged conical rollers between said upper and lower plates, and a roller alining radial arm interposed between two adjacent rollers of said circular train to keep the rollers from becoming askew and to maintain them each in proper radial arrangement, said rollers filling and covering said annular tread, and all said rollers, excepting those having radial arm engagement, directly contacting each with two adjacent rollers of the circular train, said roller alining radial arm having an integral ring fitting the annular hub of one of said center plates to keep it in its proper radial position as it travels around with the rollers, said roller alining radial arm being tapering and wider at its outer end and having curved faces contacting with the adjacent rollers, substantially as specified.

JOHN F. O'CONNOR.
